(57) **CLAIM**

The ornamental design for a toy wagon, as shown and described.

DESCRIPTION

FIG. 1 is a perspective view of a toy wagon showing my new design;

FIG. 2 is a front elevational view thereof;

FIG. 3 is a rear elevational view thereof;

FIG. 4 is a right side elevational view thereof, the left side elevational view being a mirror image;

FIG. 5 is a top plan view thereof; and,

FIG. 6 is a bottom plan view thereof.

The broken lines shown are included for the purpose of illustrating the unclaimed portions of the article and form no part of the claimed design.

1 Claim, 5 Drawing Sheets*FIG. 2*

FIG. 3

FIG. 4

FIG. 5

FIG. 6
